(57) **CLAIM**

The ornamental design for a padlock key, as shown and described.

DESCRIPTION

FIG. 1 is a front view of the padlock key showing my new design;

FIG. 2 is a back view thereof;

FIG. 3 is a left view thereof;

FIG. 4 is a right side view thereof;

FIG. 5 is a top view thereof;

FIG. 6 is a bottom view thereof; and,

FIG. 7 is a perspective view thereof.

The characteristic feature of the design resides in a padlock shaped key head.
